UNITED STATES PATENT OFFICE.

CHARLES W. H'DOUBLER, OF MADISON, WISCONSIN.

ELECTRICALLY-DRIVEN SEWING-MACHINE.

,354,603.

Specification of Letters Patent.

Patented Oct. 5, 1920.

Application filed May 12, 1919. Serial No. 296,347.

To all whom it may concern:

Be it known that I, CHARLES W. H'DOUBLER, a citizen of the United States, and resident of Madison, in the county of Dane 5 and State of Wisconsin, have invented new and useful Improvements in Electrically-Driven Sewing-Machines, of which the following is a description, reference being had to the accompanying drawings, which are a 10 part of this specification.

This invention relates to improvements in electrically driven sewing machines.

Sewing machines of the motor driven type now on the market are usually provided 15 with motors as attachments which are removably mounted on the machine. These machines, while very efficient, leave much to be desired as the motors occupy considerable space and are more or less in the way. Furthermore the said constructions are not as desirable as a unitary structure.

It is one of the objects of the present invention to overcome the before mentioned 20 objectionable features and provide an electrically driven sewing machine in which the motor is built within the standard of the machine and forms a part thereof.

A further object of the invention is to provide an electrically driven sewing machine which is built within the standard of the 25 sewing machine in a manner to permit the easy removal of the motor when desired.

A further object of the invention is to provide an electrically driven sewing machine, in which the armature shaft of the 30 motor is provided with a pulley on one end thereof in frictional engagement with the drive wheel of the machine, the pulley being provided with means whereby the same may 35 be adjusted to compensate for wear and to also adapt the same to drive wheels of various diameters.

A further object of the invention is to provide an electrically driven sewing machine 40 which is of simple construction, is strong and durable, and is well adapted for the purpose intended.

With the above and other objects in view which will appear as the description proceeds, my invention resides in the novel con-

struction, combination and arrangement of parts substantially as hereinafter described, and more particularly defined by the appended claims, it being understood that such changes may be made in the precise embodiment of my invention as come within the scope of the claims.

In the accompanying drawings I have illustrated one complete example of the physical embodiment of my invention, constructed according to the best mode I have so far devised for the practical application of the principles thereof, in which:

Figure 1 is a side view of the upper portion of my improved electrically driven sewing machine, parts being broken away and in section to show the interior construction;

Fig. 2 is an end plan view of the improved sewing machine;

Fig. 3 is a sectional view through the tubular standard of the improved sewing machine, said view being taken on the line 3-3 of Fig. 1; and

Fig. 4 is a transverse sectional view taken on the line 4-4 of Fig. 1.

Referring to the drawing, the numeral 5 indicates a tubular standard of a sewing machine, 6 a tubular overarm communicating with the standard 5 and projecting laterally therefrom, 7 a longitudinally extending drive shaft journaled in overarm 6, 8 a vertical lever or actuating rod pivotally connected to a crank 9 formed in shaft 7, and 10 a shuttle shaft operated by the rod 8. A drive or hand wheel 11 is fixed to the 75 portion of shaft 7 projected outwardly of the standard 5.

The standard 5 has one side wall thereon bulged outwardly as at 11' to form a recess 12 in which a cylindrical housing or casing 90 13 is secured, the housing 13 having secured therein the field magnets and pole pieces 14 and 15. The housing 13 may be secured in its recess 12 in any desirable manner, and has its end extending outwardly of the 95 standard 5 closed as at 16 to protect the brush members 17 engaging the commutator 18 carried by the armature 19. The shaft 20 of the armature is journalled supported by means of a bearing 21 formed centrally on 100

the closed end 16 of the housing and a bearing member 22 formed on the inner wall of standard 5 and having its bore in axial alignment with the bore of bearing 21.

- 5 The armature shaft has its inner end journaled in bearing 22 and its other end projected outwardly of the bearing 21, and has splined thereon a sleeve 23 carrying a friction pulley member (to be later described) 10 which is engaged with the periphery of drive wheel 11. In order to adapt the motor to the machine running in either direction, the brushes 17 are of the radial type and are mounted on a ring 24 and project through elongated slots 25. The ring and brush may 15 be revolved a sufficient distance with relation to the bore pieces 15 to change the polarity of said magnets and thus reverse the direction of rotation of the armature 19. 20 The brush ring 24 is held in position by binding posts 26 which extend upwardly and downwardly through the housing end 16.

The pulley member carried on the outer end of the armature shaft includes the sleeve 23 which has its inner end flanged as at 27 and its outer end threaded as at 28, and a pair of fiber plates 29 having their peripheries oppositely curved to conform with the periphery of drive wheel 11, said plates being spaced apart by means of a cork washer or plate 30. The plates 29 and 30 are keyed or otherwise secured to the sleeve 23 and are held thereon by means of a washer 31 retained thereagainst by means of a nut 32 in 35 threaded engagement with the threaded end of said sleeve.

In a number of machines, the hand wheel is unbalanced and wobbles or sways from side to side in its rotation, and to compensate for this side motion, the sleeve 23 is 40 slidably splined to armature shaft 20 to prevent the pulley from moving the shaft longitudinally in its bearings and at the same time allow the pulley to follow the hand wheel. As will be obvious, the annularly 45 grooved periphery of the pulley member engaging the periphery of the hand wheel, retains the pulley in position on shaft 20.

The form of pulley just described permits 50 the taking up of any lost motion due to excessive wear, in that the further tightening of nut 32 will compress the character or other resilient material 30 in bringing the plates 29 into closer relation with each other 55 and thus reducing the arc or curvature formed thereby. The cork or other resilient material 30 also provides a frictional contact with the drive wheel 11 in that the same projects slightly above the periphery of the 60 pulley.

From the foregoing description it will be seen that the motor for driving the sewing machine is readily removable and all that is necessary to remove the same is to remove 65 the outermost plate 29 of the pulley, then re-

move drive wheel 11 and then remove the housing 13 and armature shaft from the standard 5.

It will be also seen that the position of the motor within the sewing machine standard 70 utilizes space not otherwise employed in that the standard forms a protection for the motor.

What I claim as my invention is:

1. An electrically driven sewing machine 75 comprising a tubular sewing machine head, a drive shaft, an electric motor entirely concealed within the tubular head, said motor being bodily removable from the head and having its axis substantially parallel with 80 the axis of said shaft, and a drive connection between said shaft and motor.

2. An electrically driven sewing machine comprising a tubular sewing machine head, a longitudinally extending shaft, a drive 85 wheel fixed on said shaft, an electric motor mounted in said tubular head and including an armature shaft disposed substantially parallel to the first named shaft, and drive means carried by the armature shaft and engaging the drive wheel.

3. An electrically driven sewing machine comprising a tubular sewing machine head including a supporting arm and a laterally extending arm, a shaft journaled in one of 95 the arms, and an electric motor mounted in the other of said arms and in drive connection with the shaft, the motor having its axis substantially parallel with said shaft and being slightly to one side of the arm in 100 which it is mounted whereby an imaginary line drawn perpendicular through the axis of said shaft will pass through the motor to one side of the axis thereof.

4. An electrically driven sewing machine 105 comprising a tubular sewing machine head, a drive shaft journaled therein, a drive wheel fixed to the drive shaft, an electric motor located in the tubular head and having an armature shaft substantially parallel 110 to the drive shaft, and a pulley fixed to the armature shaft and in frictional engagement with said drive wheel.

5. An electrically driven sewing machine comprising a tubular sewing machine head 115 including a supporting standard and a laterally extending arm, a drive shaft journaled in said lateral arm and having one end projected outwardly thereof, a drive wheel fixed to the projected end of said shaft, an electric motor disposed in said standard and having an armature shaft substantially parallel to the drive shaft, and a pulley member fixed to the armature shaft and engaged with the drive wheel, said pulley being adjustable to vary its friction with the drive 125 wheel.

6. An electrically driven sewing machine comprising a tubular sewing machine head 120 including a supporting standard and a laterally extending arm, a drive shaft journaled in said lateral arm and having one end projected outwardly thereof, a drive wheel fixed to the projected end of said shaft, an electric motor disposed in said standard and having an armature shaft substantially parallel to the drive shaft, and a pulley member fixed to the armature shaft and engaged with the drive wheel, said pulley being adjustable to vary its friction with the drive wheel.

wheel on the shaft, an electric motor mounted in the tubular head and including an armature shaft, and a pulley slidably secured to the armature shaft and in frictional engagement with said drive wheel.

5. An electrically driven sewing machine comprising a sewing machine head, a drive shaft, a drive wheel on the shaft, an electric

motor mounted juxtaposed the drive shaft and wheel and including an armature shaft, and a pulley slidably secured to the armature shaft and in frictional engagement with said drive wheel.

In testimony whereof, I affix my signature.

CHARLES W. IPDOUBLER.
